HIGH FREQUENCY ELECTRON TUBE

Barremore B. Brown, Morristown, and Leslie Kovach, Whippany, N. J., and John W. Seachrist, Lancaster, Pa., assignors to Radio Corporation of America, a corporation of Delaware

Application February 27, 1953, Serial No. 339,316

13 Claims. (Cl. 315—36)

This invention relates to high frequency electron tubes in which elements in the tube form an appreciable portion of a high frequency circuit. More particularly this invention relates to high frequency electron tubes wherein the electrode structure is completely enclosed in a vacuum envelope.

Heretofore such structures have proven extremely complex from the standpoint of their manufacture and have presented serious problems in connection with providing adequate adjustment and tuning, cooling of various parts, and a shock-proof structure while maintaining simplicity and ease of manufacture as well as an overall high degree of precision, long life and low cost. In connection with such high frequency devices, the frequency at which the device is intended to operate determines the size of parts such as electrodes, tuning devices and the like. Thus, size may not readily be varied in accordance with desired thermal dissipation.

Serious problems have been encountered in the past in providing a structure having stability over a long useful life. One specific problem relates to providing composite seals such as glass or ceramic to metal which are capable of withstanding the high temperature bake-out process necessary to long useful life and stability. Thus, in the past an inordinate amount of time and cost went into providing an adequate support structure and envelope which heretofore proved to be useful only with the particular device in hand and no others.

It is therefore a principal object of this invention to provide a structure for a high frequency electron tube particularly adapted for enhanced merit and long life.

Another object is the provision of a stem and support structure for a high frequency device wherein all composite seals such as ceramic or the like to metal are relatively small and all are located at one part of the device, which structure is adapted for use in a wide variety of high frequency electron tubes, and which structure is readily fabricated and tested outside the vacuum envelope of the device in which it is to be ultimately utilized.

Another object is the provision of such a device wherein a stem and mount structure is provided in conjunction with a radio frequency structure adapted for adjustment and tuning, all being arranged to ensure enhanced life, as well as ease in manufacture.

Still another object is the provision of a magnetron structure wherein a stem and mount structure is provided in conjunction with a high frequency structure adapted for adjustment and tuning, all being arranged to ensure enhanced life, efficient cooling, as well as ease in manufacture.

In accordance with this invention a unitary stem and mount structure is provided suitable for supporting a tuning mechanism as well as the electrodes of a high frequency electron tube such as a magnetron; the mount structure including a good thermal path for cooling an anode by conduction as well as means for adjusting the tuning of the device. The seals incorporated in

2

the mount structure which form part of the vacuum envelope lend themselves to pre-testing prior to sealing-in of the device. The mount is sealed to a simple glass envelope, the outline of which is unbroken by the passage therethrough of other members.

Still other objects as well as advantages of this invention will be apparent from the following description when read in conjunction with the accompanying drawing in which:

10 Figure 1 is a sectional view taken on line 1—1 of Figure 2 of a tunable magnetron constructed in accordance with this invention:

Figure 2 is a sectional view thereof taken on the line 2—2 of Figure 1;

15 Figures 3 and 4 are transverse sectional views taken on lines 3—3 and 4—4, respectively, of Figure 1; and

Figure 5 is a plan view of the magnetron partially broken away for convenience.

20 One type of high frequency electron tube in which this invention is advantageously used is the magnetron. Therefore, while this invention will now be described in detail in connection with such a device, it is to be understood that this invention is not to be limited to magnetrons but is also useful in other high frequency tubes.

25 Referring now to the drawings in detail, electron device 10, in this instance a tunable multi-cavity magnetron, comprises a hermetically sealed vacuum tight composite glass and metal envelope which, as shown, includes tubular dielectric bulb 11 of glass. Envelope bulb 11 is unbroken in outline except at one end where it is sealed to a dielectric disc or button-like stem member 11' of glass which is sealed at 13 to a member 12 of relatively thin cross-sectional thickness and which is generally tubular. Member 12 is metallic and is constituted of such metals as will readily seal to glass such as the well known glass sealing alloys. Tubular member 12 extends into envelope bulb 11 and at its external end has an inwardly turned flange brazed vacuum tight at its periphery 14 to an elongated tubular member 15 intermediate the ends thereof. Thus, the member 12 serves as a means for joining the glass disk 11' and the tubular metal member 15 in air or vacuum tight relation. As clearly shown, tubular member 15 has a thick wall and is substantially thicker in cross section than tubular member 12. Furthermore, tubular member 15 has one end extending through tubular member 12 into bulb 11. The composition of tubular member 15 is particularly chosen to provide a high conductive thermal path and may be copper or the like. Tubular member 15 is connected adjacent its other end to a massive copper mounting disc 16 by means of which electron device 10 may be rigidly mounted in suitable apparatus.

55 Coaxially mounted with respect to tubular member 15 and extending through the same is elongated tubular member 17 which, as will be more fully pointed out hereinbelow, functions as a tuning rod and also as an exhaust tubulation. Tubular member 17 is in snug sliding engagement with a metallic disc 18 through which it extends; disc 18 being connected to tubular member 15, as indicated, at the end 19 thereof. One end of tubular member 17 extends inwardly into bulb 11 beyond the inner end of tubular member 15. The other or outer end of tubular member 17 extends outwardly beyond the outer end of tubular member 15 and affords a tubulation which is pinched off in the well known manner to seal it vacuum tight at the proper time. The interior of tubular member 17 opens into the interior of bulb 11 through one or more passage ways 20 at the inner end thereof formed by a plunger 21 rigidly connected thereto as shown. Adjacent the inner end of tubular member 17 an annular disc 22 is mounted thereon

and sealed thereto vacuum tight at 23 as by brazing or the like. The periphery of disc 22 is connected in a vacuum tight manner to a thin walled flexible member 24 which functions as a bellows and which is in turn sealed to the inner end of tubular member 15. As 5 will be more clearly pointed out, the foregoing arrangement permits mechanical adjustment to be made between the centrally located tubular member 17 and the remainder of the thus far enumerated component parts of electron device 10. This follows from the fact that bellows 24 is formed by the thin flexible wall having a plurality of folds as shown which renders the same axially extensible and retractable.

To intermediate tubular member 15 which extends in the region between outer member 12 and innermost member 17, a massive highly thermally conductive support member 25 is connected and as shown bridges bellows 24. Specifically, support member 25 is a U shaped yoke having a centrally located aperture in its base through which tubular member 15 passes and is joined thereto. Support member 25, as was pointed out in connection with tubular member 15 and mounting disc 16, is of good thermal conductive material and is joined to member 15 so as to reduce heat isolation to a minimum.

It may be well to point out at this time that the structure thus far described constitutes a highly useful support and lead-in subassembly. During the manufacture of electron device 10, bulb 11 and disc 11' are initially two separate and distinct parts. As most clearly shown in Figures 2 and 3, disc 11' has a plurality of lead-in pins 26 sealed therethrough and arranged in an annular array having a relatively large diameter. As previously indicated disc 11' is sealed to member 12 and only after the assembly of electron device 10 is otherwise complete is disc 11' joined to bulb 11 by well known glass to glass sealing techniques. One extremely important advantage of the present construction resides in that only one composite glass to metal seal is involved while the usually troublesome metal to metal seals are not only mainly maintained small in area but now may be tested to determine the efficiency thereof before being incorporated in a finished electron device. Thus, all the vacuum tight joints of the completed device except the pinch-off of member 17 and the seal joining disc 11' to bulb 11 are readily tested. Only such subassemblies free of defects are utilized to complete the assembly of device 10, thereby making possible a substantial reduction in the cost thereof.

One type of device in which our invention has proven particularly advantageous is electron device 10 shown by way of illustration and which further includes a cavity resonator 27 which forms a tuning cavity closely coupled through an iris to a multicavity magnetron anode 28. Cavity resonator 27 has two sets of side walls 29, 29' and an end wall 30 having an H-shaped iris opening 31 formed therein. The pair of opposed side walls 29 have extensions 29'' (Figure 1) which are rigidly bolted to the free ends of support member 25 and have large areas in contact to form a good heat exchange connection. A pair of opposed spaced apart elongated metallic plates 32 are each connected at one end thereof to end wall 30; iris 31 being located with the bar portion of its H shape extending centrally through the portion of end wall 30 between plates 32 and parallel to the latter. A second pair of metallic plates 33, each connected to end wall 30, the corresponding one of opposed side walls 29 and one of the plates 32, serve to maintain the latter in parallel spaced relation. As described, cavity resonator 27 when excited has an electric field distribution therein having maximum intensity or concentration in the region between parallel plates 32. It is to be understood that the walls and plates of resonator 27 are of conductive metal or the like such as copper.

Each of the opposed side walls 29' has an aperture,

the apertures being in opposed relation with a cup-shaped member or shield 34 extending through each of the apertures into the cavity of resonator 27. Cup-shaped members or shields 34 are each connected to and supported from one of the walls 29' and each has a slot 35 formed in the base thereof. As most clearly shown in Figure 2, shields 34 form wells or recesses in walls 29' in each of which an electron gun structure 36 is suspended from a sheet of insulative material such as mica 37 each of which is securely connected to one of the side walls 29'. Leads 38 extend in spaced relation to one of the electrodes of the guns 36 and at their other ends are each connected to a lead-in pin 26. The leads 38 for each gun 36 are sandwiched between one of the mica sheets 37 and a second mica sheet 39 also supported from side walls 29' as shown in Figures 2, 3 and 4. Magnetic pole pieces 40 are mounted one behind each of the guns 36 and connected to walls 29'.

Each gun 36 comprises three spaced electrodes including a cathode 36', an apertured control grid 36" and an apertured accelerating electrode 36''. The shield 34 of each gun 36 acts as the electron collector for the other depending on which gun is being operated.

As most clearly shown in Figure 1, tuning plunger 21 is slidably inserted between parallel plates 32 and has the same width as the plates. Movement of central tubular member 17 is transmitted to plunger 21, axial movement of which allows tuning over the frequency range of the device which may, for example, be from approximately 6575 to 6875 megacycles.

Magnetron anode 28 is a conventional multiple vane double strapped structure comprising an anode block 41 having a cylindrical chamber in which are mounted a central cathode 46 and an annular array of radial vanes 41' forming cavity resonators 41'' therebetween, as clearly shown in Fig. 1. Anode block 41 is connected to end wall 30, as well as plates 32 and 33, in good heat exchange relationship and is provided with an aperture 41''' which opens into one of the resonators 41'' and 40 communicates with iris 31. Thus magnetron anode 28 is closely coupled to cavity resonator 27. Anode block 41 is provided with a second H-shaped iris 42 by means of which the magnetron is closely coupled to an output wave guide not shown. The output wave guide is readily mounted adjacent the outside of the end of bulb 11 and closely coupled through the glass wall to the magnetron anode 28. An annular disc 43 connected to anode block 41 carries an annular disc-shaped mica 44 and snubbers 45. The snubbers 45 engage the interior surface of bulb 11 and serve to firmly position the free end of the structure centrally therein. Magnetron anode 28 additionally comprises the usual magnetic pole pieces 47. The leads for the magnetron electrodes such as the anode, cathode and heater leads are also joined to lead-in pins 26. This is most clearly shown in Figure 5 where lead 48 is shown extending from one end of cathode 46 to one of the lead-in pins 26.

While the electronic operation of such devices as electron device 10 is described in considerable detail in an article entitled "A 7000 megacycle developmental magnetron for frequency modulation" by H. K. Jenny, appearing at page 202 of the RCA Review, volume XII, No. 2, dated June 1952, it is not believed necessary to treat the subject at such great length herein. However, it will be well to point out that during operation of such a device the heat generated in anode block 41 is conducted to cavity resonator 27 and in turn conducted to support member 25 by way of extensions 29''. Similarly, the heat generated during operation of one or the other of the modulating guns 36 is conducted to support member 25. As was pointed out, support member 25 affords a highly conductive thermal path and, together with intermediate tubular member 15, conducts the heat generated within the envelope of electron device 10 to the exterior thereof. The arrangement of lead-in pins

26 about a circle having a relatively large diameter affords a highly desirable electrical isolation between the various leads.

From the foregoing, it is apparent that there is provided a highly compact rigid structure which lends itself to the high degree of precision required in the manufacture of such devices. The structure shown may be readily mounted in the apparatus with which it coacts without requiring any complicated manipulations to be performed. While this invention has been described in great detail in connection with a tunable multiple cavity magnetron, it is believed apparent that applicants' invention is also suitable for use with other high frequency electron devices wherein the internal structure of the device constitutes appreciable portions of the electrical circuit, thereby precluding employment of the usual practice of increasing the size of such elements, as for example the anode, in order to improve the thermal dissipation characteristic thereof. By arranging the various leads and the tuning at one end of the envelope, as well as providing the required heat dissipation or cooling through the same end, the other end of the device is available for coupling to an output circuit such as a wave guide in an extremely simple manner. Therefore, it is not intended that this invention be limited to the exact construction set forth but to claim all modifications thereof that come within the scope of the appended claims.

In the claims, the term "electrode assembly" refers to the electrodes supported by the "stem structure" (11', 12, 15, 17 and 25). As shown in the drawing, this assembly would include one or more of the magnetron anode block 28, cathode 46, tuning resonator 27 and plunger 21, and modulating guns 36.

What we claim is:

1. A high frequency electron tube comprising a vacuum envelope including a hollow dielectric body, an electrode assembly and a stem structure supporting said electrode assembly in said hollow dielectric body, said stem structure comprising a dielectric member, an elongated metallic tubular member sealed through said dielectric member, said dielectric member being sealed to said hollow dielectric body and closing the same, means including an exhaust tubulation closing said tubular member to the external atmosphere, an array of lead-in members surrounding said tubular member and sealed through said dielectric member, and a yoke connected to said tubular member and to said electrode assembly, all the members sealed through said envelope being located at the end portion of said envelope which includes said stem structure, said electrode assembly being supported substantially solely by said tubular member and said yoke.

2. A high frequency electron tube comprising an electrode assembly, a vacuum envelope including a stem structure and a hollow dielectric body enclosing said electrode assembly, said stem structure comprising a pair of coaxial metallic tubular members, one of said tubular members being open to the interior of said envelope and sealed to the atmosphere, means joining said tubular members together in vacuum tight relation, a support member connected to the other of said tubular members and to said electrode assembly and forming substantially the sole support for said electrode assembly, a dielectric member sealed in vacuum tight relation with said other tubular member and sealed to said dielectric body and closing the same, and an array of lead-ins sealed through said dielectric member and connected to said electrode assembly, said lead-ins and tubular members forming the sole direct current connection through said envelope to said electrode assembly.

3. A high frequency electron tube, comprising an electrode assembly, a vacuum envelope including a stem structure and a hollow dielectric body open at one end and enclosing said electrode assembly, said stem struc-

ture comprising a pair of coaxial metallic tubular members, the inner one of said members being open to the interior of said envelope and sealed to the atmosphere, flexible means joining said tubular members in vacuum tight relation, said inner tubular member being movable with respect to said outer tubular member, the outer one of said tubular members being highly thermally conductive, a dielectric member sealed vacuum tight to said hollow dielectric body and closing the latter, means joining said dielectric member vacuum tight to said outer tubular member, an array of lead-ins sealed through said dielectric member and spaced around said outer tubular member, a massive metallic support member connected to said outer tubular member and to said electrode assembly and forming substantially the sole support for said electrode assembly, and said lead-ins and said tubular members forming the sole direct current conductors into said envelope.

4. An electron tube, comprising an envelope including at least two coaxial metallic tubular members one within the other, the inner one of said tubular members having ends extending beyond the outer tubular member, means connecting inner end portions of said tubular members in vacuum tight manner, the other end of said inner member being sealed vacuum tight, said envelope including a hollow dielectric body portion through which said tubular members extend, means joining said dielectric body portion vacuum tight to said outer tubular member intermediate the ends thereof, a cathode, an anode including a cavity resonator adjacent said cathode, a second cavity resonator electrically and thermally closely coupled to said anode, and means connected to said second cavity resonator and to said outer tubular member supporting the former from the latter, said means forming a highly conductive thermal path and closely thermally coupled with said second cavity resonator and said outer tubular member.

5. An electron tube, comprising an envelope including a dielectric portion forming an enclosure, a cathode and an anode including a first cavity resonator adjacent said cathode in said enclosure, means for tuning said first cavity resonator including a second cavity resonator closely electrically coupled to the first cavity resonator and closely thermally coupled to said anode, coaxial concentric tubular members forming a reentrant portion of said envelope, the inner of said tubular members being open to the interior of said envelope and sealed to the atmosphere, means joining said tubular members in air tight relation, and a highly thermally conductive support member connected to said second cavity resonator and to one of said tubular members, said one tubular member being highly thermally conductive and having a portion extending outwardly of said envelope.

6. An electron tube, comprising an envelope including a dielectric portion forming an enclosure, a cathode and an anode block including a first cavity resonator adjacent said cathode in said enclosure, means for tuning said first cavity resonator and cooling said anode block including a second cavity resonator connected to said anode block in good heat exchange relationship therewith and closely electrically coupled to said first cavity resonator, said last mentioned means further including coaxial concentric tubular members forming a portion of said envelope and a highly thermally conductive member connected to one of the tubular members and to said second cavity resonator in good heat exchange relationship therewith, the inner one of said tubular members being open to the interior of said envelope and closed to the atmosphere, said one tubular member also being highly thermally conductive and having a portion extending outwardly of said envelope, and means joining said tubular members in air tight relation.

7. An electron tube, comprising an envelope including a dielectric portion forming an enclosure, a cathode and an anode block in said enclosure, said anode block in-

cluding a first cavity resonator adjacent said cathode, means for tuning said first cavity resonator and cooling said anode block including a second cavity resonator and coaxial concentric tubular members, said second cavity resonator being connected to said anode block in good heat exchange relationship therewith and closely electrically coupled with said first cavity resonator, the inner one of said tubular members extending axially through another one of said tubular members and having one end portion thereof open to the inside of said enclosure, means sealing the other end of said inner tubular member to the atmosphere, flexible means connected to said inner tubular member and said other tubular member and joining them in air tight relation with the inner tubular member movable with respect to the other tubular member, a tuning plunger connected to said inner tubular member and movable therewith and extending into said second cavity resonator for tuning the same, and a highly thermally conductive member rigidly connecting said other tubular member to said second cavity resonator and supporting the latter in good heat exchange relationship with said other tubular member, said other tubular member being highly thermally conductive and having a portion extending outwardly of said envelope.

8. An electron tube, comprising an envelope including a dielectric portion forming an enclosure, a cathode and an anode block in said enclosure, said anode block including a first cavity resonator adjacent said cathode, means for tuning said first cavity resonator and cooling said anode block including a second cavity resonator and at least one highly thermally conductive tubular member, said second cavity resonator being connected to said anode block in good heat exchange relationship and closely electrically coupled to said first cavity resonator, means connecting said second cavity resonator to said tubular member in good heat exchange relationship within said envelope and supporting said second cavity resonator, said tubular member having a portion extending outwardly of said envelope, and means including an exhaust tubulation sealing said tubular member.

9. An electron tube, comprising an envelope including a dielectric portion forming an enclosure, a cathode and an anode block in said enclosure, said anode block including a first cavity resonator adjacent said cathode, means for tuning said first cavity resonator and cooling said anode block including a second cavity resonator and at least one highly thermally conductive tubular member, said second cavity resonator being connected to said anode block in good heat exchange relationship and closely electrically coupled to said first cavity resonator, means connecting said second cavity resonator to said tubular member in good heat exchange relationship within said envelope and supporting said second cavity resonator, said tubular member having a portion extending outwardly of said envelope, means including an exhaust tubulation sealing said tubular member, and a plurality of lead-ins for supplying an input to said anode and cathode and connected thereto and extending through the wall of said envelope adjacent said tubular member.

10. An electron tube, comprising an envelope including a dielectric portion forming an enclosure, a cathode and an anode block in said enclosure, said anode block including a first cavity resonator adjacent said cathode, means for tuning said first cavity resonator and cooling said anode block including a second cavity resonator and at least one highly thermally conductive tubular member, said second cavity resonator being connected to said anode block in good heat exchange relationship and closely electrically coupled to said first cavity resonator, means connecting said second cavity resonator to said tubular member in good heat exchange relationship within said envelope and supporting said second cavity resonator, said tubular member having a portion extending outwardly of said envelope, means including an exhaust tubulation sealing said tubular member, means for modu-

5 lating said second cavity including an electron gun, said electron gun including a plurality of electrodes mounted on said second cavity resonator, and a plurality of lead-ins for supplying an input to said anode and cathode and electrodes, said lead-ins all extending through the wall of said envelope adjacent said tubular member.

11. An electron device, comprising an envelope including a dielectric portion forming an enclosure, a cathode and an anode block in said enclosure, said anode block including a first cavity resonator adjacent said cathode, means for tuning said first cavity resonator and cooling said anode block including a second cavity resonator and coaxial concentric tubular members, said second cavity resonator being connected to said anode block in good heat exchange relationship therewith and closely electrically coupled with said first cavity resonator, the inner one of said tubular members extending axially through another one of said tubular members and having one end portion thereof open to the inside of said enclosure, means sealing the other end of said inner tubular member to the atmosphere, flexible means connected to said inner tubular member and said other tubular member and joining them in air tight relation with the inner tubular member movable with respect to the other tubular member, a tuning plunger connected to said inner tubular member and movable therewith and extending into said second cavity resonator, and a highly thermally conductive member rigidly connecting said other tubular member to said second cavity resonator and supporting the latter in good heat exchange relationship with said other tubular member, said other tubular member being highly thermally conductive and having a portion extending outwardly of said envelope.

12. An electron tube, comprising an envelope including a dielectric portion forming an enclosure, a cathode and an anode block in said enclosure, said anode block including a first cavity resonator adjacent said cathode, means for tuning said first cavity resonator and cooling said anode block including a second cavity resonator and coaxial concentric tubular members, said second cavity resonator being connected to said anode block in good heat exchange relationship therewith and closely electrically coupled with said first cavity resonator, the inner one of said tubular members extending axially through another one of said tubular members and having one end portion thereof open to the inside of said enclosure, means sealing the other end of said inner tubular member to the atmosphere, flexible means connected to said inner tubular member and said other tubular member and joining them in air tight relation with the inner tubular member movable with respect to the other tubular member, a tuning plunger connected to said inner tubular member and movable therewith and extending into said second cavity resonator for tuning the same, a highly thermally conductive member rigidly connecting said other tubular member to said second cavity resonator and supporting the latter in good heat exchange relationship with said other tubular member, said other tubular member being highly thermally conductive and having a portion extending outwardly of said envelope, means for modulating said second cavity resonator including an electron gun, said electron gun including a plurality of electrodes mounted on said second cavity resonator, and a plurality of lead-ins connected to said anode, cathode and electrodes for supplying an input thereto, said lead-ins being sealed through said envelope wall adjacent said other tubular member.

13. An electron tube, comprising an envelope including a dielectric portion forming an enclosure, a cathode and an anode block in said enclosure, said anode block including a first cavity resonator adjacent said cathode, means for tuning said first cavity resonator and cooling said anode block including a second cavity resonator and at least one highly thermally conductive tubular member, said second cavity resonator being connected to said anode block in good heat exchange relationship and closely

electrically coupled to said first cavity resonator, a massive highly thermally conductive yoke supporting said second cavity resonator and connected thereto in good heat exchange relationship, said yoke having an aperture formed therethrough, said tubular member extending through said aperture and connected to said yoke in good heat exchange relationship, said tubular member having a portion extending outwardly of said envelope, said envelope including a portion of relatively low thermal conductivity joined to said tubular member, and means

10 including an exhaust tubulation sealing said tubular member.
